CIRCUIT INTERRUPTER

Herbert J. Crabbs, Wilkinsburg, Pa., assignor to
 Westinghouse Electric & Manufacturing Com-
 pany, East Pittsburgh, Pa., a corporation of
 Pennsylvania

Application October 20, 1939, Serial No. 300,368

27 Claims. (Cl. 200—162)

My invention relates generally to electric circuit interrupting devices, and more particularly to electric switches.

A primary object of my invention is to provide a switch of novel construction, which will have a longer life and be relatively easy to operate compared to switches known heretofore.

In relatively large capacity switches, the contact pressures are necessarily high, and considerable difficulty has been experienced in opening and closing such switches. Normally in opening switches of this type, a greater amount of force is necessary to start or break away the switch blade, especially if the switch has been closed for any length of time or if there is any corrosion present.

It has been proposed to provide some sort of force multiplying means effective to initially move the blade a short distance in its opening movement to assist in breaking away the blade, and it has further been proposed to make the break contacting portions of such switches of limited extent in the direction of opening movement of the switch, so that the switch blade may be substantially disengaged upon a relatively small movement.

Another object of my invention is to provide a novel limited contact arrangement for a blade type switch.

It is a further object of my invention to provide a blade type switch having a limited contact arrangement which is capable of being entirely disengaged by force multiplying means.

A disadvantage of the use of force multiplying means for breaking open switches results from the fact that with the multiplication of force obtained, a corresponding diminishing travel results, hence such a means can be practically utilized only to move a switch blade extremely short distances, and thereafter direct application of the available force has been employed to complete the opening movement of the switch blade. Inasmuch as these switches are usually manually operated, the available force is limited, and may be insufficient to easily complete the switch opening movement.

Consequently, another object of my invention is to provide a switch blade with a substantially frictionless movable mounting, so that the switch blade may be moved to full open position with a minimum of effort on the part of the operator.

Another object of my invention is to provide a switch hinge construction embodying frictionless limited area contact structure.

Still another object of my invention is to pro-

vide a switch blade construction embodying limited area contact portions, so that different contact portions are relatively movable to permit more perfect engagement of the blade and tongue contact portions, and at the same time better distribute and equalize contact pressures.

In switches of the types embodying split blades, or split tongues, contact pressure is usually obtained by passing a bolt or the like through the split member, and the bolt is tightened to stress spring washers provided thereon, any desired amount. This can be conveniently done at the hinge end of a switch where the bolt usually serves as the switch blade pivot. However, at the break end of the switch, this construction requires cutting away of a portion of the break contact to accommodate the bolt.

Another object of my invention therefore, is to provide novel contact pressure means for a switch, which is intimately associated therewith.

Another object of my invention is to provide limited contact means for an electric switch, yieldingly mounted on parts of the switch.

These and other objects of my invention will become more apparent when considered in connection with the following description and attached drawings, wherein I have disclosed preferred embodiments of my invention:

Figure 1 is a front view of a disconnecting switch constructed in accordance with my invention;

Fig. 2 is a side view of the switch shown in Fig. 1;

Fig. 3 is a side elevational view of one of the sides of a split blade used in the switch shown in Figs. 1 and 2;

Fig. 4 is an enlarged cross-sectional view of the hinge end of the blade side shown in Fig. 3 and illustrating the initial formation of the blade for receiving a limited contact insert;

Fig. 4a is a view similar to Fig. 4 but showing the contact inserts in place;

Fig. 5 is an end elevational view of the break end of the blade shown in Fig. 3;

Fig. 6 is a view similar to Fig. 5 but showing the blade before the inserts have been added;

Fig. 7 is across-sectional view of the break end of the switch shown in Figs. 1 and 2 and showing the blade slightly separated from the plane of the break tongue;

Figs. 8 and 9 are more or less diagrammatic views showing the blade and break tongue of the switch as shown in Figs. 1 and 2 at various stages of engagement;

Fig. 10 is a side elevational view of a switch similar to that shown in Figs. 1 and 2 but showing a different operating mechanism for the blade, the parts being shown on a reduced scale;

Fig. 11 is a side elevational view of a modified form of disconnecting switch;

Fig. 12 is an enlarged partial cross-sectional view taken along the line XII—XII of Fig. 11;

Fig. 13 is an enlarged partial cross-sectional view taken along the line XIII—XIII of Fig. 11; and

Fig. 14 is a view similar to Fig. 12 showing a slightly modified form of limited contact structure.

In the form of my invention shown in Figs. 1 to 9, inclusive, and referring first particularly to Figs. 1 and 2, I have illustrated therein my invention embodied in a disconnecting switch mounted on a supporting base 6 by means of the vertically spaced insulators 2 and 4, respectively. The insulators 2 and 4 may be made of any desired insulating material, such, for example, as porcelain, glass, or the like. Suitably secured on the outer end of the cap piece for the insulator 2, as by the machine screws 8, I have provided an angularly extending support member 10 which is substantially T-shaped in cross-section. The support 10 includes the cross piece 12 and the intermediate stem or web portion 14. Two sets of hinge tongues 18 are rigidly mounted on the support 10 by the horizontal spaced bolts 16 which pass through apertures in the hinge tongues 18 and in the support 10. The bolts 16 are secured in position by lock washers and nuts 17. Each hinge tongue 18 includes an intermediate straight tongue 20 and spaced outer tongues 22 having upper straight portions which are suitably spaced from the intermediate tongue, 20 and lower portions bent inwardly as at 24 to be located closer to the intermediate tongue 20 to form a terminal for the particular hinge tongue 18. Spacing sleeves 25 are mounted on the bolts 16 between the tongues of each set, and spacing sleeves 27 are mounted on bolts 16 between the sets of tongues 18. A split blade 26 is provided for each hinge tongue 18. Each blade includes the spaced parallel blade sides 28 and 30. Each side has one end thereof received between the intermediate hinge tongue 20 and an outer hinge tongue 22, and a threaded rod 32 extends through apertures in the upper ends of the hinge tongues and the adjacent ends of the blade sides 28 and 30 of both blades 26, and is provided with resilient washer elements 33 positioned at the outer sides of each hinge tongue 18, which washer elements are initially stressed and maintained in such predetermined stressed condition by the nuts 34 on the threaded rod 32 and lock nuts 36. The blades 26 are provided with limited contacting portions 40 for engaging the adjacent surfaces of the hinge tongues which contact portions will be hereinafter described in greater detail.

The insulator 4 has mounted on its cap piece an angularly extending support 42 similar to the support 10. The support 42 is substantially T-shaped in cross-section and includes a head 44, and a stem or web portion 46. Bolts 48 pass through spaced apertures in the upper end of the support and in the sets of break tongues 52, to rigidly mount the break tongues on the support. The bolts 48 are maintained in position by lock washers and nuts 50. Each break tongue set 52 includes an intermediate straight tongue 54 and spaced outer tongues 56, the lower por-

tions of which are straight and the upper portions beyond the bolt 48 being bent inwardly as at 58, to lie closer to the intermediate tongue 54 to serve as a terminal portion for the break tongue. The break tongues 54 and 56 are maintained in spaced relation by the tubular spacing member 49 mounted on the bolts 48, and they are maintained in spaced relation with respect to the other set of break tongues 52 by the tubular spacer member 51 mounted on the bolts 48 between the two sets of tongues 52. A threaded rod 60 extends through aligned apertures in the break tongues and has mounted thereon at opposite sides of each set of tongues 52, resilient washer elements 66 which are maintained under a predetermined stress by the nuts 62 engaging the washers which, in turn, are maintained in position by the lock nuts 64. The blades 26 are provided with inwardly opening notches 68 for receiving the threaded rod 60 when the blade is in the closed position with respect to the break tongues 52.

Pivotedly mounted on the blades 26 adjacent the break tongues 52 is a camming-out member 72, which is pivotedly mounted on the pin 70 which extends through apertures in the blades 26 and is maintained in position by any suitable means, such, for example, as by cotter pins or the like. The camming-out member 72 is substantially T-shaped in form and includes the stem or leg portion 74 extending in between the blades 26 and which has an eccentric aperture for receiving the pivot pin 70. The camming-out member 72 also includes a head or cross portion having enlarged ends 76 substantially overlying each blade 26. The upper and lower edges 78 and 79 of the ends 76 form stops for limiting the pivotal motion of the camming-out member with respect to the blades 26. As stated before, the camming-out member 72 is pivotedly mounted on an eccentric axis with respect to the blades 26 so as to provide a cam portion 80 on the intermediate stem 74 of the camming-out member 72, which is engageable with a fixed cam member 82 formed integral with the support 42.

The blades and break tongues are provided with limited area contacting portions as shown at 84 which are arranged to be entirely disengaged by a relatively slight separating movement of the blades 26 and the hinge tongues 52. The enlarged portions 76 of the camming-out member are spanned by an operating pin 81 to which a link of any desired suitable operating mechanism may be pivotally connected, for opening and closing the switch, or this pin 81 may be engaged by any suitable manually operable insulated operating member, such, for example, as a hook stick operating member.

It will be clear, especially from Fig. 2, that if it is desired to open the switch, it is merely necessary to exert a pull on the camming-out member 72 in an outwardly, or downwardly direction to rotate the same in a general counterclockwise direction about its pivot pin 70. Due to the relatively greater distance between the pivot pin 70 and the operating pin 81 compared to the distance between the pivot pin 70 and the cam portion 80 of the camming-out member 72, it is obvious that a greater mechanical advantage is thus obtained to initially break away and move the blades 26 a short distance away from the break tongues 52. The limited contacting portions on the blade and break tongues are arranged, as will be hereinafter described in detail, so that the mechanical advantage obtained

by the camming-out member is used to entirely disconnect or disengage the contacting portions of the blades 26 and the break tongues 52. Thus, when the stop portion 78 of the camming-out member 72 is moved from the position shown in Fig. 2 until it engages the blades 26, the blade will be moved sufficiently to be entirely disengaged from the break contact, and thus the only opposition to the following application of direct force to move the blades to a wide open position, is merely the friction encountered at the hinge end of the blade.

As shown in Figs. 3, 4, and 4a, the hinge end of the blade is provided with a hinge pin aperture 86 and an annular raised contacting portion 40. This contacting portion 40 is preferably in the form of an insert which is inserted in slots 88 formed in the blade. The inserts 40 are placed in the slots and secured therein by a pressing operation which separates a portion of the material of the blade adjacent the slot and bends it over the insert in what is ordinarily termed a swaging operation. This bent over portion of the blade is shown at 90 in Fig. 4a. The inserts 40 as shown in Fig. 4a preferably have their outer surfaces convex in form so as to obtain substantially line annular contact between the blades 26 and the hinge tongues 18. The inserts 40 may be of any suitable conducting material, but inasmuch as they are in the form of inserts, they are preferably made of a material which is better able to withstand the high friction due to the relatively high pressures exerted, especially in large capacity switches by resilient washers 38, and at the same time, they may be made of a material which is less susceptible to corrosion and may be of better conducting qualities than the material of the blades 26. The blades 26 are preferably formed of a suitable conducting material, such as copper or the like. The inserts 40, however, are preferably made of a noble metal, such as silver, or instead of being entirely made of such a metal, they may be bimetallic in form with a base portion of a baser material, such, for example, as copper or the like with an outer coating of a noble metal.

It is believed obvious from the foregoing that the only contact between the blades 26 and the hinge tongues 18 will be substantially annular line contacts between the inserts 40 on the blades and the contact tongues.

The break end of each blade is initially formed as shown in Fig. 6 with longitudinally extending slots 92. Straight inserts 84 are provided in the slots 92, which inserts may be of the same construction and material as the inserts 40, and are secured in the slots 92 by a pressing or swaging operation in the same manner described in connection with the hinge end inserts 40. However, as seen particularly in Figs. 5 and 7 to 9, the upper inserts in the break end of the blade extend laterally of the blade a greater distance than the lower inserts 94. The break tongues 52 as shown in Fig. 7 are also provided with inserts which fit into dovetailed grooves in the break tongues, respectively, with the upper insert 96 having its outer surface flush with the outer surface of its respective outer break tongue, and the lower inserts 98 extend an appreciable distance beyond the contiguous surface of the break tongues.

In the opening and closing movements of the disconnecting switch equipped with the break contact arrangement described above, the blade

and break tongue, while slightly separated, will appear as in Fig. 7. It is apparent that upon continued movement of the blade towards the break tongue from this position, because of the different lateral extent of the inserts both on the blade and tongues, these parts will not engage at all until they reach the position shown in Fig. 8, which is very near the full closed position, whereupon the upper contact inserts on the blade engage the upper ends of the break tongues, while the lower contact inserts on the blade are positioned to engage at the same time the lower inserts on the break tongue. Continued movement a relatively slight distance will bring the switch to the fully closed position illustrated in Fig. 9. It is thus apparent that in this embodiment of my invention, I have provided a disconnecting switch which requires but a relatively slight movement to entirely engage or disengage the break end of the blade from the break tongue, and this is accomplished furthermore by providing two contacting portions of the blade and break tongue in the closed position of the switch, which are spaced on opposite sides of the center line of the switch blade to provide a balanced structure while at the same time obtaining complete separation or engagement of the break tongue by a relatively slight movement of the blade relative to the tongue, which movement is entirely accomplished by the camming-out member before the stop portion 78 thereof engages the blade in the opening movement of the switch.

In Fig. 10 I have shown a disconnecting switch on a greatly reduced scale which is similar to that shown in Figs. 1 to 9, and having a blade 26 which instead of being operated by a camming-out member as is the case for the switch shown in Figs. 1 to 9, is connected for operation by a rotatable crank or toggle member 100 which is rotatably mounted at the point 101 and has its free end pivotally connected to one end of a connecting or toggle link 102, which has its opposite end directly pivotally connected to the blade 26 as at 104. As shown in this figure, in full lines, the parts are in the closed position of the switch; it will be apparent that the link 100 and link 102 form a toggle which then is at its dead-center point. In other words, the pivot points 101, 103 and 104 will be substantially aligned. It will, therefore, be apparent that only a relatively slight movement of the drive toggle link 100 will be necessary to entirely engage or disengage the blade 26 and fixed contact 52 and that this motion takes place closely adjacent to the dead-center position of the toggle. The dotted line position of the parts in Fig. 10 indicates the position at which the contacting inserts on the blade and tongue, and hence the blade and tongue themselves will be entirely disengaged. Inasmuch as it is well known in the art that the greatest mechanical advantage for tending to move the link 102 longitudinally is obtained substantially at the dead-center position of the toggle links 100, 102, it is apparent that I have here, too, provided force multiplying means for initially opening a disconnecting switch blade which is effective or which has its greatest effect while the blade is being engaged or disengaged from the blade tongue and thereafter the operating means is capable of moving the blade a greater distance relative to the movement of the primary operating member with a lesser mechanical advantage. It should be noted in connection with the embodiment shown in Fig. 10 that the greatest mechanical advantage

of the blade operating mechanism is utilized, not only for opening the switch but also for closing the switch, this being contrasted to the camming-out feature of the operating means shown in Figs. 1 and 2 which is operable only to disengage the blade from its cooperating break contact.

In Figs. 11 to 13 I have illustrated a slightly modified form of disconnecting switch which includes the supporting insulators 108 and 110 made of material similar to the insulators described in the first embodiment. The insulator 110 has secured to its outer end as by the machine screws 119, a hinge tongue structure 112 which includes an integral laterally extending terminal portion 114. A split blade 113 includes spaced blade sides 106 positioned on opposite sides of the break tongue 112 with each blade side 106 being composed of separate longitudinal portions 115 and 117. As shown more particularly in Fig. 13 the blade 113 is pivotally mounted on the hinge tongue 112 by means of the hinge bolt 116 passing through the blade sides and hinge tongue and resilient washers 120 are located on the hinge bolt at the outer sides of the split blade. A nut 118 is engaged with the bolt 116 to provide an initial stress on the resilient washers 120. The washers 120 are provided with a peripheral inwardly extending flange 122 which fits in a corresponding groove in the outer surfaces of the blade 113 to maintain the portions 115 and 117 of each blade side in assembled relation. The outer sides of the hinge tongue 112 and the inner sides of each blade side 106 are provided with annular grooves for the reception of a plurality of conducting and bearing ball members 121. These ball members 121 are preferably formed of any suitable conducting material such as copper or the like or they may be of noble metal such, for example, as silver. However, the preferred form is bimetallic with an inner core of a base conducting metal, such as copper, with a coating of a noble metal such as silver.

The insulator 108 carries at its outer end a break tongue 124 which includes a laterally extending terminal portion 125. The break end of the blade 113 is extended beyond the break tongue 124 to accommodate a combined latch release and camming-out structure, which includes an operating member 128 pivotally mounted between the lower blade side portions 117 on the bolt 126, with a resilient strip 127 being secured by the bolt 126 on the opposite sides of the blade 113. Each of the strips 127 has an upper inturned end which is freely received in an elongated aperture 129 formed in the upper blade side portions 115, to aid in maintaining the blade side portions 115 and 117 against separation at this end of the switch. The latch release and camming-out member 128 has an outer enlarged apertured portion 130 adapted to receive a hook stick operating member or the like, and includes an inner laterally extending latch operating and cam portion 132. The portion 132 extends laterally outwardly through an aperture 152 in the rear blade side 106, as viewed in Fig. 11, to be engageable with the inclined surface 134 on the latch 136 mounted at the rear of the switch. The inclined surface 134 of the latch terminates in a shoulder or hook portion 153 which engages in the aperture 152 to maintain the blade locked in its closed position. The latch 136 is pivotally mounted at its lower end on the pivot pin 138 which, in turn, is supported by the spaced pivot supports 139, integral with the break tongue structure 124. The latch

136 has an integral laterally extending bearing portion 140 which is apertured to receive the pivot pin 138 and also functions to support a coil spring 142, which has one end 144 thereof engaging a fixed portion of the tongue, and the other end 146 thereof engages a knob 148 integral with the latch 136. The spring is stressed in a manner to constantly urge the latch 136 to a latching position with respect to the aperture 152 in the blade side.

In operating the switch or in moving it to open position from the position shown in Fig. 11, a book stick or other operating member is inserted in the aperture 130 of the member 128 and pull 15 is exerted which will tend to move the member 128 in a clockwise direction about its pivot 126. This movement of member 128 will first cause engagement of the cam portion 132 thereof with the inclined surface 134 of the latch, and cause 20 rotation of the latch out of the apertures 152 against the action of spring 142. This movement of the latch continues until the hook portion 153 is removed from the aperture 152 at which time 25 a stop portion 154 on the lower end of the latch engages a portion fixed on the terminal 125 to stop the pivotal movement of the latch under the influence of the member 128. The cam portion 132 of the member 128 will at that time be at an intermediate position relative to the aperture 152. From this point on, therefore, a prying-out or force-multiplying action is obtained by 30 reaction of cam portion 132 on latch surface 134 for a short distance, or until the cam portion 132 reaches the other side of the apertures 152 in the 35 blade, whereupon the operating lever 128 will go solid with the blade and the blade is then moved from such a partly open position to any desired wide open position by a direct application of the 40 available force. Obviously, in the closing movement of the switch the inclined surface 134 of the latch 136 will engage the inner edge of the blade 113 and be cammed out to ride along the 45 outer surface of the blade until the blade reaches its closed position when the latch is free to move into the aperture 152 under the influence of the spring 142. As is the case with the switch shown in Figs. 1 and 2, no mechanical advantage is obtained in the closing movement of the blade in 50 this form of my invention.

It is, therefore, obvious that I have provided in this form of my invention as in the form illustrated in Figs. 1 and 2 a relatively greater mechanical advantage for initially moving the blade 55 a short distance in the opening movement of the blade, further opening movement of the blade being accomplished by a direct application of the available force.

Secured to the break contact 126 adjacent the 60 insulator 108 are a pair of diverging arcing horns 156 (only one of which is shown) which are secured to the break tongue in any desired manner, such, for example, as by the bolts 158.

The break tongue structure of this embodiment of my invention is particularly shown in Fig. 12, wherein I have illustrated a pair of longitudinally extending, outwardly flaring arms 160 having their inner ends secured to the break tongue 124 in any desired manner, such, for example, as by soldering, welding, or the like. The outer ends of the arm 160 are formed with inwardly convex portions 162 having a coating or layer 164 of suitable contacting material thereon, preferably of a noble metal such as silver or the like. The resilient arms 160 are preferably of

any suitably resilient conducting material, such, for example, as a phosphor-bronze alloy. The lower blade sections 117 are provided with limited contacting insert portions 172 secured flush thereto, and adapted to be engaged by the contacts 164 in the closed position of the switch. The upper blade sections 115 are provided with resilient contact supporting arms 166 similar to the arms 160 and include at their upper ends, inwardly convex contact portions 168 which may be covered or coated with a layer 170 of suitable material similar to the material 164 on the lower contact supporting arms. The break tongue 124 is provided at its upper end with a limited contact 174 on the opposite sides thereof which may be in the form of inserts of a noble metal or at least a metal differing from that of the tongue.

It is obvious that the contacting portions of the blade and tongue in this form of my invention as in the form described in connection with Figs. 1 to 10 will be entirely engaged or disengaged by a relatively slight movement of the blade and here, too, the parts are so constructed and arranged that this slight movement is obtained entirely by the cam action or force-multiplying action of the combined cam and latch release member 128.

In Fig. 14 I have shown a slightly modified form of a disconnecting blade break end construction, wherein the resilient contact supporting members 180 and 186 on the break tongue and blade respectively are all located between the planes of the sides 106 of the blade. To accomplish this the blade sides 106 are shown as being spaced slightly further apart than in the embodiment of Fig. 12, but this construction has the advantage of insuring against accidental contact of portions of the blade and tongue, other than at the limited contact portions thereof. The resilient contact supports 180 and 186 are similar in structure to the supports 160 and 166 of the embodiment shown in Fig. 12. The supports 180 have outwardly convex contact supporting portions 182 which may have an outer coating or layer 184 of a noble metal secured thereto for engagement with the inserts 192 on the inner surfaces of the blades. The inserts 192 on the blade and inserts 194 on the tongue are similar to the inserts 174 and 172 shown in the embodiment of my invention shown in Fig. 12. The resilient supports 186 which are secured to the inner sides of the blade sides 106 have inwardly convex contact portions 188 which may have a contacting layer 190 on the outer side thereof. It is obvious that here, too, but a relatively slight movement of the blade relative to the break tongue is necessary to entirely connect or disconnect the blade and tongue, thus taking advantage of a cam construction such as that shown in Fig. 1 or 11 in the same manner as the contact structures shown in those figures.

It should be noted that one advantage of a switch, such as is shown in Figs. 11 to 14, employing a split blade side 106 with the separate side portions 115 and 117, shown in these figures, is that where a plurality of points or lines of contact are used between the blade and the hinge and the break tongues, better alignment of the blade and tongues and better contact at the several points or lines is obtained, because the contacts of each of the blade side portions 115 and 117 are free to find their own contact. Thus, as viewed in Fig. 12 any disalignment or bending of the contact supporting portions 166 and 160 will not result in any twisting of the blade which might cause undesired engagement of the blade

proper and tongue, because each of the sections 115 and 117 may move laterally sideways with respect to each other to properly locate their contacting portions with respect to the cooperating contact portions of the break tongue. Another advantage of this construction is readily apparent from an inspection of Fig. 11 where it is obvious that the entire width of the break tongue is available for engagement with the longitudinally extending limited contacts on the blade tongue. This is not true of the constructions shown in Figs. 1 and 2, for example, where a bolt is provided extending through the tongue and interrupting one of the break contacting portions.

Another advantage of the construction shown in Fig. 11 resides in the ease of operation of this type of switch, which is especially important in connection with large heavy, high capacity switches, where relatively high contact pressures must be used. As previously stated, the camming-member 128 is designed to move the blade sufficiently to entirely disengage the blade from the break contacts, all other movements of the blade being under the influence of a force, which is in effect directly applied to the blade. However, due to the particular construction of the hinge end of my switch shown in Fig. 11, this is not a disadvantage because the hinge is in reality, from one standpoint, a ball bearing hinge and the friction to be overcome in it will be relatively slight since it involves rolling rather than sliding frictional parts. This is an important feature, because even with the substantially annular line contact at the hinge end of a switch, such as is shown in connection with the embodiment of Figs. 1 and 2, considerable effort may be necessary to move the blade against the friction of such hinge construction after or before engagement with the break tongue, especially in large capacity switches where very high contact pressures are highly desirable, if not necessary.

From the foregoing it is apparent that I have provided a switch having limited contacting portions between the switch blade and its hinge and break tongue, with the contacting portions at the break end of the switch being the sole engagement between the blade and break tongue, and being so constructed and arranged that the blade is entirely engaged with, or disengaged from, the break tongue by a relatively slight movement of the blade, which movement at least when opening the switch is accomplished by force-multiplying means, thus leaving only the friction of the hinge end of the blade to be overcome in other movements of the blade. Furthermore, I have provided in one embodiment of my invention a blade hinge construction which is materially easier to operate than what has been known heretofore, and in fact will be substantially frictionless. It is also apparent that in one embodiment of my invention I have disclosed an example of movement-multiplying means which has its maximum effect or mechanical advantage for moving a switch blade the relatively slight amount necessary to completely engage or disengage the blade from its break contacts. This blade operating means is also effective in both the opening and closing movements of the switch. It is also apparent that I have provided in one embodiment of my invention a novel blade construction wherein the blade is constructed with at least two entirely separate sections which are relatively movable with respect to each other so that each section of the blade is able to find its own contact independently of the other to thus

provide better alignment of the blade and its hinge and break tongues, and also to relieve any stresses which might otherwise be set up in the blade or its tongues due to any disalignment of these parts.

Having described preferred embodiments of my invention in accordance with the patent statutes, I desire that it be distinctly understood that my invention is not to be limited to the particular embodiments disclosed therein, inasmuch as it will be obvious, particularly to persons skilled in the art, that many changes and modifications may be made in the structures disclosed, without departing from the broad spirit and scope of my invention. Therefore, I desire that my invention be not limited except by what is expressly set forth in the following claims.

I claim as my invention:

1. In a switch, a blade member movable into and out of engagement with a contact member, said members being of a good electrical conducting material, one of said members being split to receive the other of said members, at least one of said members having limited area contact portions projecting from at least one surface thereof towards the confronting surface of the other member when said members are in engagement, with said contact portions on said one surface projecting different distances and arranged so that said contact portions engage said other member only when the switch is substantially closed.

2. In a switch, a blade member movable into and out of engagement with a contact member, said members being of a good electrical conducting material, one of said members being split to receive the other of said members, the other of said members having limited area contact portions thereon projecting from opposite sides thereof, the portions on each side projecting different distances and arranged to engage said first member only when the switch is substantially closed.

3. In a switch, a blade member movable into and out of engagement with a contact member, said members being of a good electrical conducting material, one of said members being split to receive the other of said members, at least one of said members having on one side thereof spaced, parallel, limited area contact portions projecting from said one side towards the confronting surface of the other member when said members are in engagement, with said contact portions projecting different distances and arranged so that said contact portions engage said other member only when the switch is substantially closed.

4. In a switch, a blade member movable into and out of engagement with a contact member, said members being of a good electrical conducting material, one of said members being split to receive the other of said members, at least one of said members having spaced parallel limited area contact portions projecting from one side thereof to engage the other member when said switch is closed, said contact portions extending at an angle to the line of movement of said blade member and being spaced in the direction of said movement, the contacting portions nearest said other member projecting to a lesser extent than remote contacting portions, and projecting limited area contact portions on said other member positioned to engage said first mentioned contacting portions of lesser extent in the closed position of the switch, whereby no

parts of said members are ever engaged except the contacting portions thereof in substantially the closed position of the switch.

5. In a switch, a blade member movable into and out of engagement with a contact member, said members being of a good electrical conducting material, one of said members being split to receive the other of said members, at least one of said members having spaced parallel limited area contact portions projecting from one side thereof to engage the other member when said switch is closed, said contact portions extending at an angle to the line of movement of said blade member and being spaced in the direction of said movement, the contacting portions nearest said other member projecting to a lesser extent than remote contacting portions, and limited area contact parts on said other member positioned to engage said contact portions, respectively, in the closed position of the switch with the contact part adapted to engage said contact portion of lesser extent, projecting from said other member, whereby said members are never engaged except when said contact portions and contact parts are in engagement, substantially in the closed position of the switch.

6. In a switch, a blade member movable into and out of engagement with a contact member, said members being of a good electrical conducting material, one of said members being split to receive the other of said members, at least one of said members having spaced elongated, parallel, limited area contacting portions on one side thereof spaced in a plane arranged at an acute angle to the plane of movement of said blade means, and arranged so that said contacting portions engage the other of said members only when the switch is substantially closed, and said contacting portion located between the sides of said split member at least in the closed position of said switch.

7. In a switch, a blade member movable into and out of engagement with a contact member, said members being of a good electrical conducting material, one of said members being split to receive the other of said members, said members each having on at least one side thereof elongated, parallel, limited area contacting portions spaced in the direction of movement of said blade member and offset laterally thereof and arranged to engage the other of said members only when the switch is substantially closed.

8. In a switch, a split break tongue, a blade mounted for movement into and out of engagement between the sides of said tongue, said blade and tongue being of a good electrical conducting material, and said blade and tongue each having on at least one confronting side thereof, limited area contact portions spaced in the direction of movement of said blade member and offset laterally thereof.

9. In a switch, a split break tongue, a blade mounted for movement into and out of engagement between the sides of said tongue, said blade and tongue being of a good electrical conducting material, and said blade and tongue each having on at least one confronting side thereof, elongated limited area contact portions spaced in the direction of movement of said blade member and offset laterally thereof and extending at an angle to the direction of movement of said blade.

10. In a switch, a split break tongue, a blade mounted for movement into and out of engagement between the sides of said tongue, said blade and tongue being of a good electrical conduct-

ing material, and said blade having projecting limited area contact portions on each side thereof facing the sides of said tongue when said members are engaged, with the portions on each side projecting different distances.

11. In a switch, a blade member movable into and out of engagement with a contact member, said members being of a good electrical conducting material, one of said members being split to receive the other of said members, each of said members having a plurality of elongated limited area contact portions offset substantially laterally of the line of movement of the blade and spaced in said direction of movement, and located relative to said members so that said portions are engaged only substantially in the closed position of the switch, and said members being out of engagement at all other positions of the switch.

12. In a switch, a split break tongue, a blade mounted for movement into and out of engagement between the sides of said tongue, said blade and tongue being of a good electrical conducting material, and said blade having projecting limited area contact portions on each side thereof, with the portions on each side projecting different distances and with the portions on each side of the blade projecting the lesser distance being positioned on the blade closest to said tongue, and inwardly facing limited area contact parts on the sides of said tongue positioned to engage said last mentioned blade contact portions in the closed position of the switch.

13. In a switch, a blade member movable into and out of engagement with a contact member, one of said members being split to receive the other of said members, in spaced relation, and opposed limited area contact portions carried by each of said members, and said portions on each member positioned to engage the outer sides of the other member.

14. In a switch, a blade member movable into and out of engagement with a contact member, one of said members being split to receive the other of said members, in spaced relation, and opposed limited area contact portions resiliently supported by each of said members for engagement with the other member.

15. In a switch, a blade member movable into and out of engagement with a contact member, one of said members being split to receive the other of said members in spaced relation, said split member having opposed inwardly extending limited area contact portions for engaging the outer sides of said other member, and said other member having opposed outwardly extending limited area contact portions for engaging the outer sides of said split member.

16. In a switch, a break contact tongue, and limited area contact portions resiliently supported on opposite sides of said tongue and facing in opposite directions, said portions being spaced inwardly from the outer end of said tongue.

17. In a switch, a blade member movable into and out of engagement with a contact member, and each of said members carrying a resilient limited area contact spaced therefrom for engagement with the other of said members.

18. In a switch, a base, a break contact tongue member projecting outwardly from said base and having spaced limited area contact portions at least on one side thereof, with the innermost one of said portions projecting laterally beyond the outermost one of said portions.

19. In a switch, a flat switch blade member of

electrical conducting material having spaced, limited area contacting portions of different lateral extent on at least one side of said member.

20. A switch member having spaced limited area contact portions on one surface thereof, at least one of which projects beyond said surface of said member and the other of said portions.

21. In a switch, a blade member movable into and out of engagement with a contact member, one of said members being split to receive the other of said members, at least one of said members embodying laterally spaced limited area contact portions, the sides of said split member including separate relatively movable portions for cooperation with said contact portions respectively, and means urging the sides of said split member towards each other, so that each of said separate portions may find its respective contact.

22. In a switch, a split blade member pivotally mounted on a hinge tongue for movement into and out of engagement with a contact, said blade having spaced limited area contact points with said contact and hinge tongue, each side of said blade including separate longitudinal parts, and means for urging said blade sides towards each other, but permitting limited relative movement of adjacent blade parts.

23. In a switch, a split blade member pivotally mounted on a hinge tongue for movement into and out of engagement with a contact, said blade having spaced limited area contact points with said contact and hinge tongue, each side of said blade including separate longitudinal parts, and means for urging said blade sides towards each other including resilient means engaging openings in the outer sides of said blade for preventing sideways separation of said blade parts while permitting limited lateral movement thereof.

24. In a switch, a split blade member pivotally mounted on a hinge tongue for movement into and out of engagement with a contact, said blade having spaced limited area contact points with said contact and hinge tongue, each side of said blade including separate longitudinal parts, and means for urging said blade sides towards each other including resilient washers mounted on a bolt connecting said blade sides, said washers having inwardly extending portions extending into openings in the outer sides of the blade, for preventing undue separation of said blade parts.

25. In a switch, a blade member movable into and out of engagement with a contact member, one of said members being split to receive the other of said members in spaced relation, said split member having opposed inwardly extending limited area contact portions for engaging the outer sides of said other member, and said other member having opposed outwardly extending limited area contact portions for engaging the sides of said split member at points spaced from said inwardly extending portions at the closed portion of said switch, and said contact portions being confined between the planes of the sides of said split member.

26. In a switch, a blade member pivotally mounted on a hinge contact member for movement into and out of engagement with a break contact member, said members being of a good electrical conducting material, annularly arranged limited area contact means between said blade and hinge contact members, and at least one of said blade and break contact members having limited area contacting portions spaced in the direction of movement of said blade mem-

ber and laterally thereof so as to be engaged only when the switch is substantially closed.

27. In a switch, a split blade member pivotally mounted on a hinge tongue for movement into and out of engagement with a contact, said blade having spaced limited area points of contact with said contact, each side of said blade

including separate longitudinal parts on which said limited area contacts are mounted, respectively, and means for urging said blade sides towards each other, but permitting limited relative movement of adjacent blade parts.

HERBERT J. CRABBS.
